UNITED STATES PATENT OFFICE.

VICTOR EMANUEL FERMIER, OF FORNEY, TEXAS.

TOY.

1,332,822.

Specification of Letters Patent.

Patented Mar. 2, 1920.

Application filed July 21, 1919. Serial No. 312,214.

To all whom it may concern:

Be it known that I, VICTOR E. FERMIER, a citizen of the United States, and a resident of Forney, in the county of Kaufman 5 and State of Texas, have invented certain new and useful Improvements in Toys, of which the following is a specification.

My invention is an improvement in toys, and has for its object to provide a toy of the 10 motion type, wherein a figure is mounted on a wheeled support and is controlled by the movement of the vehicle to move in imitation of the normal movement of the figure.

15 In the drawings:

Figure 1 is a side view of the improved toy;

Fig. 2 is a bottom plan view;

Fig. 3 is a front view, with the body of 20 the support in section;

Fig. 4 is a side view of the wheel;

Fig. 5 is a vertical section of the wheel;

Fig. 6 is a perspective view of a portion 25 of the platform.

20 In the present embodiment of the invention, a suitable support is provided, consisting of a platform 1 to whose under face is secured a pair of cheek or bearing plates 2 and a tongue 3 is secured between the 30 bearing plates at one end of the platform, the tongue inclining upward as shown.

These cheek plates are also connected at the front of the platform by a connecting block 4 and a wheel 5 is journaled between 35 the cheek plates, between the tongue and the filling block 4. This wheel is connected to the cheek pieces by means of crank pins 6—7, and each of these pins consists of a portion 6 which is journaled in the adjacent 40 cheek piece at the axis of the wheel, and a portion 7 offset laterally with respect to the portion 6 and having at the end thereof a cross plate 8 which is secured to the adjacent face of the wheel.

45 A link 9 is pivoted to each crank pin on the portion 7 thereof, and these links sup-

port a figure 10 which, in the present instance, is that of a hare or rabbit. The figure represents the hare in the act of running, and since the crank shafts 6 are spaced 50 at angular intervals of somewhat more than forty-five degrees with respect to each other, an eccentric movement will be given to the figure. The rear end of the figure, with the support moving forwardly from the position of Fig. 1, will first be moved slightly 55 upward and then downward. The front end will first move downward and then upward, but the eccentric arrangement of the crank journaled pins will impart an eccentric 60 movement to the figure to simulate the galloping of a rabbit.

I claim:

1. A motion toy comprising a support, a 65 wheel for the support, cranked pins connecting the wheel with the support, each pin comprising a portion axial to the wheel and journaled in the support and a portion eccentric to the wheel and secured thereto, a figure, and links connecting the figure with 70 those portions of the cranked pins adjacent to the wheel.

2. A motion toy comprising a support, a 75 wheel for the support, cranked pins connecting the wheel with the support, each pin comprising a portion axial to the wheel and journaled in the support and a portion eccentric to the wheel and secured thereto, a figure, and a connection between the said 80 figure and those portions of the cranked pins adjacent to the wheel for supporting and moving the said figure.

3. A motion toy, comprising a wheeled 85 support, crank pins connecting the wheel with the support, each pin comprising two portions offset laterally with respect to each other, one portion being journaled in the support and the other portion being secured eccentrically to the wheel, a figure, and connections between the figure and the first 90 named portions for the purpose specified.

VICTOR EMANUEL FERMIER.
